UNITED STATES PATENT OFFICE.

JOHN M. TAYLOR, OF RADNOR, PENNSYLVANIA, ASSIGNOR TO DIAMOND STATE FIBRE COMPANY, OF BRIDGEPORT, PENNSYLVANIA, A CORPORATION OF PENNSYLVANIA.

METHOD OF PARCHMENTIZING FABRIC.

1,350,685.

Specification of Letters Patent. Patented Aug. 24, 1920.

Application filed July 24, 1917. Serial No. 182,452.

To all whom it may concern:

Be it known that I, JOHN M. TAYLOR, a citizen of the United States, residing in Radnor, Delaware county, Pennsylvania, 5 have invented Methods of Parchmentizing Fabric, of which the following is a specification.

One object of this invention is to provide a process for so treating a parchmentized 10 web or laminated parchmentized webs to remove the parchmentizing chemicals, as to avoid the objectionable results of shrinkage, which shall permit of a material shortening of the length of the washing apparatus re- 15 quired, and which shall permit the amount of wash water to be reduced to a minimum with a view to facilitating as well as cheapening its subsequent concentration.

These objects and other advantageous 20 ends I secure as hereinafter set forth, reference being had to the accompanying drawings, in which,

Figure 1 is a plan to some extent diagrammatic, illustrating one form of apparatus 25 for carrying out my invention;

Fig. 2 is a vertical section on the line 2-2, Fig. 1, further illustrating the apparatus preferably employed; and

Fig. 3 is an elevation of a detail of the 30 mechanism preferably employed in carrying out my invention.

In the above drawings, 1-6 represent tanks designed to contain independent bodies of wash water. The first tank is 35 provided with means for supporting two reels or spools 7 and 8 and likewise contains guide rollers 9, 10, 11, 12, etc., for directing a web of parchmentized material to or from either of said rolls. Each of the tanks 2-6 40 contains a greater or less number of upper guide rollers 13 and lower guide rollers 14, so arranged that a web passed around them will be alternately directed up and down through the wash water within them.

The tanks 3 and 4 respectively provide 45 means for supporting a pair of reels or winding rolls 15 and 16 and the tank 6 also supports a reel or roll 17;—it being understood that there may be any number 50 of tanks or sets of tanks, of which the end tanks of each set have mounted adjacent their outer ends means for supporting a reel in such position that it shall be immediately adjacent a similar reel at the end

of an adjacent set of tanks. Any desired 55 means is provided for driving any of the reels at will and while I have illustrated a system of belts with the necessary shafts and pulleys, it is obvious that any suitable driving means or source of power may be 60 employed for this purpose; it being noted however that such driving means should preferably include mechanism such as the differential gear 20 whereby the speed of each driven reel is varied or permitted to 65 vary in accordance with the changes in the diameter of the roll of material upon it.

Under conditions of operation a web made up of one or more thicknesses of paper or similar material is run through a bath of 70 parchmentizing liquid and is thereafter acted on in the usual manner by one or more heated rollers, from which it is directed to the reel 7, for example. After any desired length of this parchmentized web has been 75 wound upon said reel it is cut and its end coming from the heated rolls is directed to a second reel 8 upon which the winding is continued. The end of the web on the first reel is thereupon directed over suitable rolls 80 to the guide roll 12 and thence to the first of the top rolls 13 of the tank 2, from whence it is carried successively down and up around the others of the guide rolls 14 and 13 through the water in said tank. It 85 is then passed to the guide rolls of the tank 3 and its end is finally carried to and wound upon the reel 15 which is turned by power.

Wash water is supplied to all of the tanks. so that the first length of the parchmentized 90 web in passing through the water in the first series of tanks, is partially freed from the parchmentizing chemicals which it contains, it being noted that after the web has passed through the water it carries a certain 95 amount of the same with it when wound into a roll so that there is a continuation of the washing action even when said web is not actually in the tank. When practically all of this web is wound on the reel 15 100 and before its end has been withdrawn from the reel 8, power is cut off from said first reel and is applied to the latter reel so that said web is drawn back from the reel 15 through the wash water in the tanks 3 and 105 2. This passage of the web alternately in opposite directions through the tanks 2 and 3 is repeated as often as is required to bring

the strength of the parchmentizing solution in the web to the same or approximately the same strength as that of the wash water.

When this condition is found to exist, the 5 web is completely wound on the reel 15, from whence it is carried to the reel 16, which is then driven so as to draw said web from the reel 15. At the same time a second length of web is run from the reel 7 on to 10 the reel 8.

When all of the first length of web has been wound upon the reel 16, it is led over the first of the upper rollers 13 of the tank 4 and thence successively around the other 15 lower and upper rollers in this and in the tanks 5 and 6, until its end is connected to the spindle of the reel 17. These last three tanks are likewise filled with wash water and obviously the movement through them 20 of the partly washed web causes further amounts of the remaining parchmentizing chemicals to be removed therefrom.

As in the case of the first washing, when practically all of this first web has been 25 wound upon the reel 17, the latter is disconnected from the source of power and the reel 16 is driven so as to draw back the web through the wash water in the tanks 6, 5 and 4. This operation is repeated until 30 the strength of the parchmentizing solution throughout the body of the web is substantially the same as that of the wash water in these tanks.

At the same time a second length of web 35 from the parchmentizing tanks and rollers is being given its first washing in the tanks 2 and 3 as previously described. Obviously there may be as many sets of tanks and reels in addition to those illustrated as may be 40 desired, although I have found that for the treatment of webs in the neighborhood of one-sixteenth of an inch and less in thickness, two or at the most three sets of washing tanks is sufficient. Moreover, the web 45 is run back and forth through any one set of tanks until the chemicals in it are removed to the extent above indicated.

As the treatment of successive lengths of 50 parchmentized web is continued, the wash water in the various sets of tanks receives increasing amounts of parchmentizing chemicals, the liquid in the tanks 2 and 3 naturally being the most concentrated and that in the remainder of the tanks decreasing in 55 concentration, depending upon their distance from the first set of tanks.

After the concentration of the wash water in the first series of tanks has reached the desired point, it is drawn off and evaporated 60 so that it may be used either directly or with the addition of suitable materials, in parchmentizing new bodies of paper web or other material. The liquid removed from the tanks 2 and 3 is then replaced by the 65 weaker solution in the tanks 4, 5 and 6,

which in turn are refilled either with clean water or by the weak washing solution from another series of tanks.

By thus washing the parchmentized web in a succession of isolated lengths by running it back and forth through tanks in which the washing solution is successively weaker or in which the water is increasingly less contaminated, I am enabled to materially increase the speed of operation, reduce the length of the washing plant as a whole and efficiently obtain more or less concentrated solutions which may be advantageously evaporated to recover the chemicals they contain.

As will be understood by those skilled in the art, after the web has been sufficiently washed, it is dried or otherwise prepared for use.

Another advantage of the invention resides in the freedom of the web to shrink during the washing operation without in any way interfering with the performance of the apparatus, for it is obvious that any changes in the length or tension of said web, occurring while it is being drawn through the tanks, can at most have no effect other than to cause a variation in the speed of revolution of the roll from which it is being drawn. As the driven roll increases in diameter and therefore tends to increase the tension on the web, the differential gear allows rotation of the roller shaft relatively to the driving pulley, to an extent sufficient to make up or compensate for, such increase 100 of diameter.

In the present case the frame of the differential gear is driven from the source of power through a supporting shaft 35 to which is secured and has loosely mounted upon it a beveled pinion 30, which meshes with a pair of beveled gears 31 and 32, respectively fixed to two pulleys 33 and 34, shown in Fig. 1 and loosely rotatable upon the supporting shaft 35. One of these 110 pulleys, as 33, through a suitable belt, drives the tank rollers 13 while the other 34 drives the reel upon which the parchmentized web is wound. In a typical case the diameter of the roll driven by this latter pulley 115 varies from twenty-two inches to sixty inches and the differential gear forms a balancing element whereby this roll decreases in speed with the increased speed of the web so as to maintain an even tension thereon at 120 all times, regardless of the increased diameter of the roll upon which said web is being wound.

It will be understood that in addition to the differential gear for each of the rolls, the latter each has a clutch 21 whereby it may be connected to or disconnected from the main driving shaft or source of power.

I claim;—

1. The method which consists in treating 130

a web with a parchmentizing liquid; and thereafter repeatedly passing said web through a body of washing liquid until the strength of the liquid within the body of the web is substantially the same as that of said washing liquid.

2. The method which consists in treating a web with a parchmentizing liquid; thereafter repeatedly passing the web through a body of washing liquid until the strength of the parchmentizing solution within the body of the web is substantially the same as that of said washing liquid; and repeatedly passing the web through a second body of washing liquid until its strength is the same as that of the parchmentizing liquid in the body of the web.

3. The method which consists in continuously parchmentizing a web of material; winding the parchmentized web onto in-

dependent rolls; successively drawing the rolled sections of the web back and forth through a plurality of independent baths of washing liquid; and finally rolling up said sections of the web.

4. The method which consists in passing a web through a parchmentizing liquid; forming a roll of the parchmentized web; drawing said web from said roll through a body of washing liquid; forming it into a second roll while maintaining it at a constant tension; and thereafter repeatedly passing the web through the body of washing liquid also while it is maintained under constant tension until the strength of the liquid within the web is substantially the same as that of the washing liquid.

In witness whereof I affix my signature.

JOHN M. TAYLOR.
